(57) **CLAIM**

The ornamental design for a communication outlet, as shown and described.

DESCRIPTION

FIG. 1 is a top rear perspective view of a communication outlet showing our new design.

FIG. 2 is a top front perspective view thereof.

FIG. 3 is a rear elevational view thereof.

FIG. 4 is a right side elevational view thereof.

FIG. 5 is a top plan view thereof.

FIG. 6 is a left side elevational view thereof.

FIG. 7 is a bottom plan view thereof; and,

FIG. 8 is a front elevational view thereof.

The broken lines represent portions of the communication outlet that form no part of the claim.
